US00D973950S

(12) **United States Design Patent** (10) Patent No.: **US D973,950 S**
(45) Date of Patent: ** *Dec. 27, 2022

(54) **HANDHELD AEROSOL GENERATOR**

(71) Applicant: **PHILIP MORRIS PRODUCTS S.A.**,
Neuchatel (CH)

(72) Inventors: **David Kuchen**, Vallamand-Dessous
(CH); **Frederic Lavanchy**, Chavornay
(CH); **Stephane Roudier**, Colombier
(CH)

(73) Assignee: **PHILIP MORRIS PRODUCTS S.A.**,
Neuchatel (CH)

(*) Notice: This patent is subject to a terminal disclaimer.

(**) Term: **15 Years**

(21) Appl. No.: **29/671,749**

(22) Filed: **Nov. 29, 2018**

Related U.S. Application Data

(62) Division of application No. 35/503,721, filed on Mar. 27, 2017 (U.S. filing date under 35 U.S.C. 384), and having an international filing date of Mar. 27, 2017, now Pat. No. Des. 870,366.
